UNITED STATES PATENT OFFICE.

JAMES P. BLAUVELT, OF NYACK, NEW YORK.

TERMINAL CONNECTION FOR SPARK-PLUGS.

1,188,445.

Specification of Letters Patent.

Patented May 4, 1915.

Application filed October 21, 1914. Serial No. 867,758.

To all whom it may concern:

Be it known that I, JAMES P. BLAUVELT, a citizen of the United States, and a resident of Nyack, in the county of Rockland 5 and State of New York, have invented a new and Improved Terminal Connection for Spark-Plugs, of which the following is a full, clear, and exact description.

The object of the invention is to provide 10 a new and improved terminal connection for spark plugs and similar devices arranged to permit of convenient attachment of a clip to the central electrode member of the spark plug and to prevent losing of the nut employed for fastening the clip in position on the spark plug.

In order to accomplish the desired result, use is made of a clip connected with an electrical conductor and provided with a bearing 20 for the nut of the spark plug to turn in, the nut serving to clamp the clip in place on the spark plug.

A practical embodiment of the invention is represented in the accompanying drawings forming a part of this specification, in 25 which similar characters of reference indicate corresponding parts in all the views.

Figure 1 is a sectional side elevation of the terminal connection as applied to a 30 spark plug; Fig. 2 is a plan view of the clip; and Fig. 3 is a side elevation of the nut for fastening the clip in position on the spark plug.

The terminal connection is shown applied 35 to a spark plug A of usual construction and having a central electrode member B on which screws a nut C for clamping the terminal clip D in position on the spark plug A, as plainly indicated in Fig. 1. To the 40 clip D is soldered or otherwise secured one end of the electrical conductor E covered by a suitable insulation F', the end of which is engaged by the split shank D' of the clip D to fasten the latter to the electrical conductor. The clip D is provided with an 45 opening D² for the passage of the member B, and the said clip D is further provided with a return bend D³ provided with a bearing D⁴ in which is mounted to rotate a journal C' formed on the upper end of the nut C so that the latter is held permanently 50 between the clip D and the return bend D³, and the nut can be readily rotated so as to screw it on the member B or unscrew it 55 therefrom. It will be noticed that when the aperture D² of the clip D is engaged

with the upper end of the electrode member B then the screw is held in proper position for screwing on the member B, and in screwing the nut C down on the member B the 60 clip D is finally clamped in position between the nut C and the collar F held on the spark plug A. The journal C' is preferably formed by providing the nut C with a reduced extension C² formed with an annular 65 groove, and the bearing D⁴ is preferably formed in the return bend D³ by providing the latter with a lengthwise extending split to provide split members having registering recesses at their opposite edges to form the 70 bearing D⁴.

By the arrangement described the split members can be readily opened to pass a journal C' into position in the bearing D⁴, after which the split members can be pressed 75 toward each other to a normal position so as to hold the journal C' in position in the bearing D⁴ with the nut C extending between the return bend and the clip D.

The terminal connection shown and described is very simple and durable in construction and as the nut C is permanently and rotatably carried on the clip D, it is evident that the said nut cannot be readily lost and the clip can be quickly connected 85 with the spark plug or removed therefrom whenever it is desired to do so.

Although I have shown and described the terminal connection as particularly applicable to spark plugs, it is evident that 90 the said terminal connection may be used for other devices of a similar nature.

Having thus described my invention, I claim as new and desire to secure by Letters Patent:—

1. A terminal connection, comprising a clip adapted to be connected with an electrical conductor, said clip having oppositely arranged and spaced non-resilient members provided with registering openings, one of the members having a slit leading from the opening out through the end thereof, and a nut having a reduced portion engaging the opening of the slotted member and having the portion thereof below the reduced portion lying wholly between the members of the clip, the slit of the clip member being of less width than the diameter of the reduced portion of the nut, whereby the nut will be permanently held in the clip. 100 105 110

2. In a terminal connection for spark

plugs having a central electrode member, a nut screwing thereon, and a clip connected with an electrical conductor and having a return bend provided with a bearing, the 5 said nut extending between the clip and the return bend and having a journal engaging the said bearing.

3. In a terminal connection for spark plugs having a central electrode member, a 10 nut screwing thereon, and a clip connected with an electrical conductor and having a return bend provided with a lengthwise extending split forming split members having registering recesses at their opposite edges 15 to form a bearing for the said nut to turn in.

4. In a terminal connection for spark plugs having a central electrode member, a nut screwing thereon, and a clip connected with an electrical conductor and having a 20 return bend provided with a lengthwise extending split forming split members having registering recesses at their inner opposite

edges to form a bearing, the said nut extending between the clip and its return bend and having a journal at the upper end engaging 25 the said bearing.

5. A terminal connection comprising a clip adapted to be connected with an electrical conductor, said clip having oppositely arranged and spaced members provided with registering openings of unequal diameter, and a nut having a reduced portion engaging the larger opening of the member, the portion of the nut except that engaging the opening being wholly between 30 and 35 the said members.

In testimony whereof I have signed my name to this specification in the presence of two subscribing witnesses.

JAMES P. BLAUVELT.
